UNITED STATES PATENT OFFICE

167,407

HUMIDIFIER

Clarence Karstadt, Santa Barbara, Calif., assignor to Birtman Electric Company, a corporation of Illinois

Continuation of abandoned application Serial No. 16,741, September 25, 1951, and abandoned application Serial No. 13,840, January 17, 1951. This application April 22, 1952, Serial No. 19,433

Term of patent 14 years

(Cl. D62—4)

To all whom it may concern:

Be it known that I, Clarence Karstadt, a citizen of the United States, residing at Santa Barbara, in the county of Santa Barbara and State of California, have invented a new, original, and ornamental Design for a Humidifier, of which the following is a specification, reference being had to the accompanying drawings forming a part thereof, in which:

Fig. 1 is a side elevational view of a humidifier showing my new design; Fig. 2 is a side elevation similar to Fig. 1 but taken at right angles to the elevation of Fig. 1. Fig. 3 is a top plan view thereof and Fig. 4 is a bottom view thereof.

This application is a continuation of my application Serial No. D. 16,741, filed September 25, 1951, which in turn was a continuation of my application Serial No. D. 13,840, filed January 17, 1951, both now abandoned.

I claim:

The ornamental design for a humidifier, as shown and described.

CLARENCE KARSTADT.
